UNITED STATES PATENT OFFICE.

CARL WELLER, OF ZURICH, SWITZERLAND.

SPRAYING APPARATUS.

1,271,107.

Specification of Letters Patent.

Patented July 2, 1918.

Application filed October 18, 1917. Serial No. 196,469.

To all whom it may concern:

Be it known that I, CARL WELLER, a citizen of the Republic of Switzerland, residing at No. 72 Mühlbachstrasse, Zurich, Switzerland, have invented certain new and useful

Improvements in Spraying Apparatus; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to improvements in spraying apparatus such as sand-blast-machines, white-washing and painting sprayers and the like and it is the object of the invention to provide means for discharging the spraying material tank and for cleaning the admission or feed member for the material to be sprayed.

Whenever sand, paint or a chemical substance in the form of grains or of a thick liquid has to pass from a tank through a passage having a comparatively narrow cross-section, there is the drawback that the passage may become clogged at its narrowest cross-section by impurities or by the formation of lumps in the sand, paint or the like, due to atmospheric influences or other causes. To clear this it is necessary to dismantle certain parts of closing and regulating devices, of which said admission member for the material forms a part, or to empty the tank, or even to perform both these operations. This results however, in great loss of time and involves considerable working expenses.

The object of the present invention is, as already generally stated, to provide means on spraying apparatus of the type referred to for emptying the material tank and cleaning the admission member for the material which, without being necessary to stop the working, render it possible to empty instantaneously the tank for the material by means of or without using compressed air and moreover enable a quick and thorough discharging and cleaning. In consequence of these improvements any foreign bodies, such as core-nails, hairs of brushes, pieces of wood, wood-shavings, stones, paper-pieces and the like, may be removed, without stopping the working or shutting off the compressed air after removal of a detachable

cover. As a result of the improvements forming the subject matter of this invention the clogged admission member for the material may also be cleaned while the apparatus is in operation.

The accompanying drawings show, by way of example, the invention applied to a sand-blast-machine.

In these drawings:

Figure 1 is a vertical section on the line I—I of Fig. 2 through a first embodiment of a sand-blast-machine.

Fig. 2 is a section on the line II—II of Fig. 1.

Fig. 3 is a front view of the sand-admission-cock.

Fig. 4 is a section on the line IV—IV of Fig. 3.

Figs. 5 and 6 are sections through said cock and parts of the casing occupied by this cock, the cock being shown in these figures in different positions.

Fig. 7 shows, partly in section, a modification of a detail.

1 is a sand tank and 2 a mixing pipe in which compressed air admitted in the direction of the arrow shown in Fig. 1 is mixed with a jet of sand fed vertically from above. 3 is a pipe through which the resulting mixture of sand and air is conveyed. A vertical pipe 4 branches off from the mixing pipe 2 at the inlet end and reaches to the upper part of the tank 1. The vertical pipe 4 is to introduce compressed air into the sand tank 1 in order to maintain constant the flow of sand from the said tank. A valve 5 and hopper 6 are for charging the sand tank 1. The admission of the compressed air to the mixing pipe 2 is controlled by means of a cock 7.

8 is a casing arranged below the sand tank 1 and connected at its upper end in an airtight manner to the tank 1 and at the lower end to the mixing pipe 2. A cock 9 is movably mounted within this casing 8. 10 is a handle for adjusting the cock 9. Cock 9 is provided with a continuous cross-hole 11 terminating at one end in the passage opening 12. The cock 9 is also provided with a hollow space 13 communicating at the end lying in Fig. 2 at the right hand end with the cross-hole 11 by means of a bore 14 while at the other end it is open. In the cylindrical part of the cock 9 surrounding the hollow space 13 is provided an aperture 15, so that the hollow space 13 is also partly

open in the circumferential direction of the cock 9. 16 (Fig. 2) denotes a cover arranged near the open end of the hollow space 13 and detachably secured to the casing 8. The latter is also provided with a passage 17 adapted to establish a communication between the cross-hole 11 and the mixing pipe 2. 18 is a cleaning pipe fixed at one end to the casing 8 and adapted to be 10 shut off by means of a cock 19. 21 is a cock mounted in the outer end of a passage 22 of the mixing pipe 2 and is for controlling the quality of the mixture of air and sand flowing into the pipe 3.

15 The passageway of the mixing pipe 2 is partly closed by a body 23 which has the form illustrated in Figs. 1 and 2. This body is fixed in proper position within the pipe by means of a plate 24 which is pressed by an 20 eccentric 25 against said body and an open portion of the pipe. Said eccentric is formed on a lever 26 pivotally mounted on a shaft 27 which is supported parallel to the axis of the pipe in eyes 28 formed on 25 the latter.

The working of the described apparatus is as follows: When cock 9 is moved into the position shown in Figs. 1 and 2 by means of the handle 10, the passages 11, 12 and 17 30 establish a communication between the sand tank 1 and the mixing pipe 2. The operator may then work with the sand jet. In the event of an obstruction occurring—and this is nearly always in the narrow passage opening 12 of the cock 9—the latter is turned so by means of the handle 10 that the passage opening 12 comes to lie oppositely to that end of the cleaning pipe 18 which lies within the casing 8 (Fig. 5).

40 The hollow space 13 is then put into communication with the mixing pipe 2 by means of the aperture 15 and the passage 17, while the communication between the mixing pipe 2 and the tank 1 is shut off. Thus, compressed air may flow into the hollow space 13 and from the latter through the bore 14 to the passage opening 12. When the cock 19 is opened the opening 12 will be cleared at once, the obstructing matter being forced 50 through the pipe 18 into the atmosphere.

If, however, the whole contents of the tank 1 are to be emptied, handle 10 is turned in such a manner that cock 9 assumes the position illustrated in Fig. 6, so that the aperture 15 establishes a communication between the hollow space 13 and tank 1. The communication between the latter and the mixing pipe 2 is thereby closed and cock 19 is turned off. After the removal of cover 55 16 the compressed air admitted into the tank 1 causes all the sand to be forced through the aperture 15 and the hollow space 13 and to be blown out into the atmosphere through the opening furnished by 60 65 the removal of the cover 16.

The attendance of such a sand-blast-machine is very easy and does not require any skill.

Thus, when for instance a cleaning of the passage opening 12 has to be effected, all 70 that the attendant has to do is to turn on cock 19 and perform only one further manipulation.

In Fig. 7, 32 denotes a by-pass branching off from the pipe 34 in front of the cock 33 mounted in this pipe 34. The other end of the by-pass 32 communicates with the space of the casing 8 occupied by the cock 9 which is similar to that shown in Figs. 1-6. 35 is a cock in the by-pass 32. The latter communicates also behind the cocks 33 and 35 with the mixing pipe 2 by means of a pipe 36. 37 denotes again a cleaning pipe provided with a cock 38.

In the event of an obstruction occurring 25 in the passage opening 12 of the cock 9, the cock 35 is turned on, the cock 33 is turned off and the cock 9 is turned so, that the openings 11 and 12 establish a communication 30 between the by-pass pipe 32 and the pipe 37, 90 so that upon an opening of the cock 38 compressed air flows through the openings 11, 12, and the pipe 37 for the purpose of removing obstructions from the passage opening 12 and force them into the atmosphere. 95 The air passing through the pipe 32 has thereby the tendency to flow along a straight line and exerts then a sucking action at the upper end of the pipe 36, so that, as the cock 35 is turned off, the air has no tendency to 100 escape from the pipe 32 through and out of the pipes 36, 2 and 3.

If the cock 35 is turned off, compressed air passes through the pipe 36 into the right hand end of the by-pass 32. When the cock 105 9 is in the position shown in Fig. 7 any obstructions in the opening 12 are then again instantly removed by the compressed air passing through pipe 36 and the right hand end of the by-pass 32.

What I claim as my invention is:

1. A spraying apparatus, such as a sand-blast-machine, white-washing or painting sprayer and the like, comprising a spraying material tank, a compressed air feed-pipe, a 115 mixing-pipe connected to said feed-pipe, means provided with a passage for the spraying material and adjustably arranged between the material tank and the mixing pipe, a member removably secured to the 120 spraying apparatus and a cleaning-pipe also arranged intermediate the material tank and the mixing-pipe and adapted to establish a communication between said adjustable means and the atmosphere, said adjustable means effecting according to its adjustment either a communication between the material tank and the mixing-pipe, or 125 between the latter and the cleaning-pipe, or, after removal of the detachable member, 130

either between the material tank and the atmosphere or between the mixing-pipe and the atmosphere.

2. A spraying apparatus, such as a sand-blast-machine, white-washing or painting sprayer and the like, comprising a spraying material tank, a compressed air feed-pipe, a mixing-pipe connected to said feed-pipe, means provided on the mixing-pipe for controlling the quality of the air and sand mixture, means for supplying compressed air from the mixing-pipe to the material tank, a casing arranged intermediate the tank and the mixing-pipe and connected with said tank and mixing-pipe, means adjustably arranged in said casing and provided with a passage for the spraying material, a cover detachably secured to said casing and a cleaning-pipe adapted to establish a communication between the casing space occupied by the adjustable means and the atmosphere, the adjustable means effecting according to its adjustment a communication between the material tank and the mixing-pipe or between the latter and the cleaning-pipe, or, after removal of the detachable cover, either between the material tank and the atmosphere or between the mixing-pipe and the atmosphere.
3. A spraying apparatus, such as a sand-blast-machine, white-washing or painting sprayer and the like, comprising a spraying material tank, a compressed air feed-pipe, a mixing-pipe connected to said feed-pipe, means provided on the mixing-pipe for controlling the quality of the air and sand mixture, means for supplying compressed air from the mixing-pipe to the material tank, a casing arranged intermediate the tank and the mixing-pipe and connected with said tank and mixing-pipe, means adjustably arranged in said casing and provided with a passage for the spraying material, a cover detachably secured to said casing, a cleaning-pipe adapted to establish a communication between the casing space occupied by the adjustable means and the atmosphere and a further pipe adapted to supply compressed air to the casing space occupied by the adjustable means, the latter effecting according to its adjustment a communication between the material tank and the mixing-pipe, or between the pipe supplying compressed air to said casing and the cleaning-pipe on the one hand and the atmosphere on the other hand or, after removal of the detachable cover, either between the material tank and the atmosphere or the mixing-pipe and the atmosphere.

4. A spraying apparatus, such as a sand-blast-machine, white-washing or painting sprayer and the like, comprising a spraying material tank, a compressed air feed-pipe, a mixing-pipe connected to said feed-pipe, means for feeding compressed air from the mixing-pipe to the material tank, a casing arranged intermediate the tank and the mixing-pipe and connected to said two parts, a cock mounted in the casing and having a passage opening for the spraying material, hand actuated means for adjusting said cock, a cover detachably secured to said casing and a cleaning-pipe adapted to establish a communication between the casing space occupied by the cock and the atmosphere, said cock effecting according to its adjustment a communication between the material tank and the mixing-pipe or between the latter and the cleaning-pipe, or, after removal of the detachable cover, either between the material tank and the atmosphere or between the mixing-pipe and the atmosphere.

5. A spraying apparatus, such as a sand-blast-machine, white-washing or painting sprayer and the like, comprising a spraying material tank, a compressed air feed-pipe, a mixing-pipe connected to said feed-pipe, means for supplying compressed air from the mixing-pipe to the material tank, a casing arranged intermediate the tank and the mixing-pipe and connected to said two parts, a cock mounted in the casing having a cross-hole terminating at one end in a passage-opening for the spraying material and having also a hollow space open at one end and communicating at the other end with said cross-hole, said hollow space being also open in the circumferential direction of the cock, a cover detachably secured to the casing opposite to the open end of the hollow space of the cock and a cleaning-pipe adapted to establish a communication between the casing space occupied by the cock and the atmosphere, said cock establishing according to its adjustment a communication between the material tank and the mixing-pipe, or, by means of the hollow space, between the latter and the cleaning-pipe, so that it is possible to blow compressed air through said passage-opening for the spraying material, or, after removal of the detachable cover, between the material tank and the atmosphere, the latter in order to empty the material tank.

In testimony that I claim the foregoing as my invention, I have signed my name.

CARL WELLER.
